United States Patent [19]

Hasegawa et al.

[11] Patent Number: Des. 313,004

[45] Date of Patent: ** Dec. 18, 1990

[54] BATTERY CHARGER

[75] Inventors: Hideaki Hasegawa, Katsuta; Yoshiro Iimura, Mito; Kazuyuki Nagahara, Katsuta, all of Japan

[73] Assignee: Hitachi Koko Company, Ltd., Japan

[**] Term: 14 Years

[21] Appl. No.: 230,345

[22] Filed: Aug. 9, 1988

[52] U.S. Cl. D13/108

[58] Field of Search D13/108; D8/68; 320/2-5, 27; 310/50

[57] CLAIM

The ornamental design for a battery charger, as shown and described.

DESCRIPTION

FIG. 1 is a front perspective view of an embodiment of a battery charger showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top view thereof;
FIG. 7 is a bottom view thereof; and
FIG. 8 is a front perspective view thereof with an inserted battery. The broken line showing of the battery is for illustrative purposes only and forms no part of the claimed design.
